CUP DISPENSER HOUSING

Fred H. Lewis, Wilmette, Ill.

Application December 9, 1947, Serial No. 143,052

Term of patent 14 years

(Cl. D52—2)

To all whom it may concern:

Be it known that I, Fred H. Lewis, a citizen of the United States, residing at Wilmette, in the county of Cook and State of Illinois, have invented a new, original, and ornamental Design for a Cup Dispenser Housing, of which the following is a specification, reference being had to the accompanying drawing, forming part thereof.

Figure 1 is a perspective view of a cup dispenser housing showing my new design; Figure 2 is a side elevational view of the same; and Figure 3 is a top plan view of the same.

The partial illustration of a paper cup shown in dash lines is for illustrative purposes only.

I claim:

The ornamental design for a cup dispenser housing, substantially as shown and described.

FRED H. LEWIS,
